Filed May 23, 1962, Ser. No. 70,248

Term of patent 14 years

(Cl. D54—1)

FIG. 10

FIG. 11

FIG. 12

FIGURE 1 is a perspective view of a clip fastener embodying my new design;

FIGURES 2, 3, and 4 are end, side, and plan views thereof;

FIGURE 5 is a perspective view of a modified form for a clip fastener, and;

FIGURES 6, 7, and 8 are end, side, and plan views respectively of the form shown in FIGURE 5;

FIGURE 9 is a perspective view of further modified form for a clip fastener, and;

FIGURES 10, 11, and 12 are end, side, and plan views respectively of the form shown in FIGURE 9.

The characterizing feature of my design for a clip fastener resides in the sinuous curvature of the bridge element thereof.

I claim:

The ornamental design for a clip fastener, as shown and described.
